UNITED STATES PATENT OFFICE.

PHILIP MILLER, OF NORWICH, CONNECTICUT.

BAND SAWING-MACHINE.

SPECIFICATION forming part of Letters Patent No. 308,188, dated November 18, 1884.

Application filed September 30, 1884. (No model.)

To all whom it may concern:

Be it known that I, PHILIP MILLER, of the city of Norwich, county of New London, and State of Connecticut, have invented certain new and useful Improvements in Devices for Sawing Logs and Felling Trees, which improvements are fully set forth and described in the following specification, reference being had to the accompanying drawings.

10 My improvement relates to a mechanical device for sawing logs into desired lengths, or for sawing off standing trees, my object being to provide a device which is portable, convenient to use, and which shall cut more rapidly than saws now in common use.

Said invention consists, first, of a portable saw-frame for band-saws, and a peculiar means for securing the same to a log or tree; second, of perforating said saw and providing lugs to engage said perforations on the pulleys around which the saw travels, to keep the saw moving continually in the same plane, and to prevent all tendency on the part of the saw to slip when in use; third, of forming the lower portion of the supporting-frame so it will clasp the back or upper edge of the saw to prevent spreading; fourth, of guide-rolls to hold the two cutting-sections in close engagement with each other when sawing a single kerf, or to regulate the length of the piece sawed off when sawing a double kerf; fifth, of means for transmitting motion and power from one pulley to its mate at the opposite end of the supporting-frame; sixth, of a suitable handle by which said frame may be elevated or depressed by the operator in charge; and, seventh, of a peculiar form of saw-tooth.

In the annexed drawings, Figure 1 is a side elevation of my complete device, the same being secured to a fallen log. Fig. 2 is a top view of the same with the supporting-frame removed. Fig. 3 is a cross-section on line $x-x$, Fig. 1, showing the form of the lower edge of the frame A'. Fig. 4 is an enlarged edgewise view of the saw-teeth; and Fig. 5 is an enlarged cross-section similar to Fig. 3, showing the relative length of the inner and outer teeth.

The top and sides of my supporting-frame A may be of wood or iron, as desired; but the lower rail, A', and stiffening-brace A², if used, should be of a thickness equal to the united thickness of the two contiguous sections of

the saw-blade, for reasons hereinafter specified. At each lower corner of the supporting-frame is secured a frame, B B', having bearings in which rotate the shafts C C', carrying with them pulleys E E'. These pulleys support the band-saw G, which, as above stated, is provided at regular distances with slots a, which engage lugs b on pulleys E E', the office of said lugs being to keep the saw in a given position and prevent its slipping on said pulleys. The frame B has secured to its lower portion a shaft, c, which is journaled in the outer ends of two or more dogs or clamps, I. When said clamps are secured rigidly to a log or tree, as shown, the shaft c forms the hinge or pivot on which the saw and its several frames and pulleys may be swung, the movement of the same being easily controlled by the handle d on the free or movable end of the frame A. These clamps I may be located one on each side of the pulley-frame, as shown, or may be both on the same side, in which case the pulley-frame is supported on the outer free end of shaft c.

Formed as a part of frames B B' are inward extensions or arms, e e', furnishing bearings for the pivots of pulleys h h'. These pulleys h h' are preferably so located relative to the saw that the two sections of said saw, after passing around the pulleys E E', are brought in contact with each other, traveling, of course, in opposite directions, but cutting a single kerf. By so running the two cutting-sections of the saw in the same kerf I find that said saw cuts much more rapidly than a single saw-blade and clears itself much better.

As a convenient and inexpensive way to apply power to my device I have formed pulley E with a grooved flange at its upper end, in which groove runs a rope or belt, K, which is kept in motion by a steam-engine located at a suitable distance from the saw, or by any other convenient power.

In cases where it is desirable to transmit power and motion from pulley B to pulley E', so that both sides of the saw may travel alike, I have arranged the system of shafts C C' and i, and the miter-gears h h', which will be readily understood from the drawings, the general arrangement being almost identical with the vertical feed in a metal-planer.

It will be evident that if the two cutting-

sections of the saw are not held in close engagement with each other there will be a constant inclination to spread and leave each other with a tendency to cramp and break. 5 said saw, especially so if sawdust is allowed to work upward between the two moving sections. To anticipate and overcome this difficulty I have grooved the lower edge of frame A', and formed the upper edge of the saw so 10 that said grooved frame rests on and holds together both of said saw-sections, as shown in Figs. 3 and 5. In Fig. 5 is also shown a parting-strip, n, formed as a part of frame A', which keeps the saw-blades slightly apart, preventing 15 unnecessary friction. In many cases, after a tree has been felled, it is necessary that the log should be cut up into cord-wood or other sections of regular length. By moving the guide-pulleys h h' apart, as indicated by dotted circles in Fig. 2, the saw-blades are separated from each other, each making its own kerf, instead of running in a single kerf, as above described. Thus it will be seen that at 20 every complete cutting of the saw two lengths or sections of the log are cut off. The teeth of my saw are formed, preferably, as in Figs. 4 and 5—that is to say, they are so filed that

as the teeth on the engaging-surfaces pass each other they make a shearing-cut, also tend to throw all sawdust outward instead of between the two sections. These inner shearing-teeth, o, have no set, and are considerably longer than the outer set-teeth, m. By thus making the shearing-teeth longer, so that they may 30 cut in advance of the set-teeth, there is a constant tendency to draw the engaging-surfaces in toward each other. 35

Having thus described my invention, I claim—

The supporting-frame having the grooved 40 section A', pulleys E E', hung rotatably in the frame A, and provided with lugs b, a band-saw perforated to engage the lugged pulleys and having its upper edge shaped to conform to the groove in section A', and the guide-rolls 45 h h', so located that they hold the inner faces of the band-saw in engagement with each other, all being combined and used substantially as and for the purpose specified.

PHILIP MILLER.
